UNITED STATES PATENT OFFICE.

RICHARD H. DUSENBURY, OF BRUNSWICK, NEW YORK, ASSIGNOR OF ONE-HALF TO THEODORE D. ROBINSON, OF SAME PLACE.

IRONING-MACHINE.

SPECIFICATION forming part of Letters Patent No. 427,469, dated May 6, 1890.

Application filed October 9, 1888. Serial No. 287,877. (No model.)

To all whom it may concern:

Be it known that I, RICHARD H. DUSENBURY, a citizen of the United States of America, residing at Brunswick, in the county of 5 Rensselaer and State of New York, have invented certain new and useful Improvements in Ironing-Machines, of which the following is a specification, reference being had therein to the accompanying drawings.

10 My invention relates to machines for ironing or polishing cuffs, collars, and the bosoms of shirts; and the objects of my invention are to provide a machine in which the ironing-board is reciprocated by mechanism 15 placed vertically under said board to produce a smooth motion the whole length of its course and at the ends thereof, and also in which a shirt band, cuff, or collar supporting roll is controlled by eccentric means, as hereinafter 20 described. I attain these objects by the mechanism illustrated in the accompanying drawings, in which—

Figure 1 is a side view of an ironing-machine constructed in accordance with my invention. Fig. 2 is a longitudinal vertical section of the same through the center thereof. Fig. 3 is a transverse vertical section on line xx of Fig. 1. Fig. 4 is a top view of the machine. Fig. 5 is a view in perspective of the 25 under side of the ironing-board. Fig. 6 is a view in perspective of the inner side of the frame carrying the band or cuff supporting roll.

In said drawings, A represents the frame 30 upon which is mounted in suitable bearings the driving-shaft B, carrying the pulley B^2 , around which may be made to pass a belt connected with a motive power. To give a smooth reciprocating motion to the support or ironing-board C, a pinion b is mounted loosely 35 upon the driving-shaft, and said pinion carries one member b' of a clutch, while the other member b^2 is connected by means of a feather or other well-known means with said shaft B. The member b^2 of the clutch can be connected or placed in clutch with the member b' by means of a lever b^3 , pivoted to the frame at b^4 , and having one end extending to the front end of the machine and the other

end forked and engaged into a circular groove 50 of the member b^2 . The pinion b meshes with a gear-wheel D, adapted to revolve upon a stud d , projecting from the bracket d^2 , secured to the frame.

The wheel D carries adjustably secured in 55 a slot d' , formed in one of its arms or spokes, a crank-pin d^3 , carrying a roller that is made to play in a vertical slot e of an arm E, vertically pendent from the carriage E^2 , carrying the ironing-board. Said carriage has two 60 axles e^2 extending across the machine, with wheels or rollers e^3 on the ends thereof, and said rollers are adapted to travel in horizontal grooves a in the sides of the frame A. Said carriage has projecting vertically therefrom at one end a short standard c , the head of which is semicircular or convex on one side at c^2 , the curve corresponding with the opening formed in the top of a shirt-bosom 65 to receive the neck of the wearer. The ironing-board has a corresponding concave recess c^3 , and between said curved surfaces the neck-band is inserted. The under side of the board is provided with a longitudinal T-shaped rib c^4 , that is made to engage with two similar 70 ribs e^4 on top of the carriage; but the arrangement of said ribs may be reversed, or other forms of connection—as a dovetail and groove—may be used. To retain the shirt-bosom or 75 its neck-band clamped upon the ironing-board, a lever e^5 is used. It is pivoted to the carriage at e^6 , and has its eccentric end made to engage with the beveled rear end of the rib c^4 of said ironing-board.

The ironing-roller F is, as usual, made hollow or chambered for the reception of gas, steam, or other heating medium. It is mounted in bearings G, adapted to slide upon and be guided in grooves formed in guide-blocks G^2 , secured to the top of the frame A. The 80 grooves in said blocks are at an angle of about forty-five degrees to their base, and the bearings G are forced up or down said grooves by means of a pair of connecting-rods g , a pair of levers H, a foot-lever or pedal H^2 , and 85 springs h . The pedal is pivoted upon a horizontal rod a^2 , uniting the two side frames A. The lower arm of said pedal has a slot to re-

ceive a horizontal rod h' , carried by the lower end of the levers H. Said levers are pivoted to the frame at h^2 , and have their upper end pivoted to the lower end of the connecting-
5 rods g, and the upper ends of said rods are pivoted to the bearing G. By the above means the ironing-roll is forced upon the ironing-board by the operator pressing upon the pedal H², and said roll is elevated by the springs 10 h, one end of which is secured to the lower portion of the levers H, and the other end presses against the frame of the machine. To transmit motion to the ironing-roll, a pulley F² is secured on one end thereof. Said pulley 15 carries a belt F³, that passes around a pulley F⁴ upon the driving-shaft B.

To permit shirt bands, collars, or cuffs to be ironed by one attendant while another may be ironing the bosom of shirt or other object, 20 the ironing-roll F is provided at one end with a roller F⁵ in continuation thereof but extending beyond the side of the frame, and under said roll F⁵ the band, cuff, or collar support on supporting-roll I is mounted upon 25 a shaft i, carried by a vertically-movable frame K. Said frame has on the inner side thereof two parallel ribs k to embrace and be guided by a vertical rib k⁴ upon the side of the frame of the machine, and said parts are retained 30 connected by means of a bolt k², inserted into said frame and passing through a vertical slot in the frame K. The lower end of this frame K has a side lug k³ to enlarge its base, against which the operator can force the eccentric upper end of the foot-lever L, pivoted 35 to the frame at l, by pressing his foot upon the pedal L² of said lever. To cause the rolls to rotate together, the shaft of rolls F F⁵ carries a gear-wheel M, with which a gear-wheel 40 N of the supporting-roll I meshes when the operator presses forward upon the pedal L².

Although the crank-pin d³, used to recip-

rocate the carriage E², is preferably secured to the wheel D, the axle d of which may be bent in the form of a crank and made to engage with the slot e of the arm E without departing from the spirit of my invention. 45

Having now fully described my invention, I claim—

1. The combination of an ironing-roll, a reciprocating carriage, its standard c, having a curved head c², and a groove in the top of said carriage, with the ironing-board, having a concave recess c³ and a longitudinal rib in the bottom thereof, and the locking-lever e⁵, pivoted to the carriage and adapted to press against said rib, substantially as described. 50

2. An ironing-machine consisting of a frame having horizontal guiding-grooves and a vertical guide-rib, an ironing-board carriage adapted to be reciprocated in said grooves, and a vertical frame carrying a roll I and adapted to be reciprocated along said rib, and means, as described, for reciprocating said carriage and the roll I, with a hollow ironing-roller adapted to rotate upon said ironing-board and roll I, substantially as and for the purpose described. 60

3. An ironing-machine provided with a horizontally-reciprocating carriage carrying a flat ironing-support and a vertically-reciprocating frame carrying a convex or cylindrical ironing-support, with means, as described, for reciprocating said ironing-supports and a hollow ironing-roller adapted to 70 rotate upon said supports, substantially as described. 75

In testimony whereof I affix my signature in presence of two witnesses.

RICHARD H. DUSENBURY.
